UNITED STATES PATENT OFFICE.

LUCAS LITTY, OF DONALDSONVILLE, LOUISIANA.

CLARIFIER.

SPECIFICATION forming part of Letters Patent No. 694,871, dated March 4, 1902.

Application filed August 12, 1901. Serial No. 71,789. (No model.)

To all whom it may concern:

Be it known that I, LUCAS LITTY, a citizen of the United States, and a resident of Donaldsonville, in the parish of Ascension and State of Louisiana, have invented a new and Improved Clarifier, of which the following is a full, clear, and exact description.

This invention relates to improvements in apparatus for automatically clarifying the juice of sugar-cane, beet-sugar, or other juices with which heat is employed for clarification; and the object is to provide an apparatus for this purpose of simple construction by means of which juices will be rapidly and thoroughly clarified in an automatic manner or without manual exertion.

I will describe a clarifier embodying my invention and then point out the novel features in the appended claims.

Reference is to be had to the accompanying drawings, forming a part of this specification, in which similar characters of reference indicate corresponding parts in all the figures.

Figure 1 is a sectional elevation of a clarifier embodying my invention, and Fig. 2 is a plan view thereof.

Referring to the drawings, 1 designates the clarifier-tank, divided into two compartments A and B, which are here shown as of rectangular form; but it is obvious that they may be cylindrical or otherwise formed without departing from the spirit of my invention. To form the compartments, the tank is divided by means of a partition 2, which extends from the bottom of the tank to a point somewhat below the top thereof. This partition 2 is provided with an outlet 3 at its lower end, controlled by a gate-valve 4, having an upwardly-extended stem 5, the object of which will hereinafter appear. At one side of the partition 2, or within the compartment B, is a retarding-partition 5^a, which extends from a point somewhat above the top of the partition 2 to a point slightly above the bottom of the tank.

At the inlet end of the tank, or within the head portion of the compartment A, is an inclined partition or baffle-plate 6, which extends nearly to the bottom of the tank, and in the space between said baffle-plate 6 and the end of the tank the material to be clarified is received through a pipe 7.

Inclined upward and outward from the top of the partition or baffle-plate 6 is a chute 8, having a solid bottom and side walls, and spaced above the solid bottom is a screen or perforated plate 9, over which an endless carrier moves for carrying scum and discharging it into a trough 10, having a pipe 11 leading to a mud-tank. The endless carrier or conveyer consists of blades 12, connected at their ends to chains 13 and 14, the chain 13 passing around sprocket-wheels 15 and 16 on the shafts 17 and 18, while the chain 14 passes around sprocket-wheels 19 and 20 on said shafts 17 and 18. The shaft 18 is extended and is provided with a sprocket-wheel 21, from which a sprocket-chain 22 extends to a sprocket-wheel 23 on the shaft of an engine 24, which is operated by exhaust-steam, as will be hereinafter described.

Arranged on the tank 1, over the partition 5, is a propelling-wheel 25, on the shaft of which is a sprocket-wheel 26, from which a chain 27 leads to a sprocket-wheel 28 on the shaft 18. 75 A steam-pipe 29 leads from a suitable boiler, and from this pipe a branch pipe 30, having a valve 31, leads into the central portion of a coil 32, arranged in the bottom of the compartment A. The ends of this coil 32 communicate through a pipe 33 with an exhaust-pipe 34, having a branch connection 35 with the motor, this branch connection being provided with a valve 36, and also forward of the connection 35 the pipe 34 is provided 85 with a valve 37. A pipe 38, having a valve 39, leads into the central portion of a coil 40, the ends of which communicate through a pipe 41 with the exhaust-pipe 34.

At the outlet end of the tank and leading 90 from a point near the bottom thereof is a discharge-pipe 42, and in this pipe 42 is arranged a regulating-pipe, consisting of the upwardly-extended members 43, in which members 44 of a connecting-section are vertically adjustable. This regulator is designed to regulate the height of liquid in the tank—that is, the height necessary to carry the scum to a point above the partition 5^a. As a means for adjusting the height of the regulator I provide 95 a screw-rod 45, which is connected at its upper end to the cross-pipe of the upper section and passes through an opening in a bar 46, connected to the members 43. The thread of

this screw-rod is engaged above and below the bar 46 by adjusting-nuts. The upper section of the regulator is provided with a vent 47.

Between the members 43 the pipe 42 is provided with a valve 48, designed to be closed when liquid is to be passed through the regulator or to be opened when the tank is to be drained. As a further means for draining the tank of any matter that might settle to the bottom thereof I provide a drain-pipe 49, in which a valve is arranged. I have shown the drain-pipe as having communication with but one of the compartments. However, each compartment may be provided with such a drain-pipe.

In operation the juice after the preparation for clarifying passes into the tank and against the partition 6 through the pipe 7. The juice passes out under the bottom of the partition 6, and when the coil 32 is covered steam is turned on by opening the valve 31. The liquid reaching the top of the partition 2 will flow over the same against the partition 5^a and underneath said partition 5^a into the compartment B. When the coil 40 in this compartment B is covered, steam is turned on by opening the valve 39. The exhaust-steam from the coils will pass to the motor 24, the valve 37 being closed and the valve 36 open, and the motor will impart motion to the endless conveyer and also to the paddle-wheel or propeller 25. The agitation of the liquid will carry the scum or blanket to the top, and the blades of the conveyer will scrape off this scum and carry it up over the sieve or perforated bottom 9, discharging it into the trough 10. Whatever liquid may be carried with the scum will pass through said sieve or perforated bottom onto the solid bottom of the chute 8 and flow back into the compartment A of the tank forward of the baffle-plate 6.

While the current induced by movements of the endless conveyer may be sufficient to draw the scum toward the chute, I find it convenient to also employ the wheel 25, the blades of which will pass closely to the top of the partition 5^a. The agitation of the wheel 25 will force said scum back toward the chute, where it will be gathered up by the endless conveyer.

The upper member 44 of the regulator is to be adjusted by means of the rod 45 and while the valve 48 is closed to keep the juice or liquid up to the top of the partition 5^a. This will by the flow of the juice over the partition 2 and under the partition 5^a cause the impurities or scum better to rise and flow over the partition 2 and seek the conveyer 12. The clarified liquid will pass out through a section of the pipe 42, thence through the regulator 43 44 to the other section of the pipe 42.

To drain the tank after closing down work, the valve 4 is to be raised and the valve 48 in the pipe 42 opened, and thus it is obvious that the liquid will flow out through said pipe 42 without passing through the regulator.

To wash out the tank, the valve in the pipe 49 may be opened and water poured in the tank.

The speed of the conveyer 12 may be regulated by more or less opening the valve 36 in the pipe leading to the motor and the more or less opening or closing of the valve 37. The partitions 5^a and 6 will cause the juice 75 to evenly spread when entering and passing under them.

While I have shown the tank as divided into two compartments, it is obvious that it may be divided into a greater number of 80 compartments, depending upon the amount of juice to be operated upon.

From the above description it will be seen that I have provided an automatic apparatus for a continuous flow of juice that will remove the impurities or scum rising to the top of the liquid and without manual manipulation. The operation may be carried out with steam at a very low temperature, thus resulting in an economy in the use of fuel. 90

Having thus described my invention, I claim as new and desire to secure by Letters Patent—

1. In a clarifier, an endless conveyer, comprising scrapers operating to remove scum 95 from liquid flowing through the tank, an inclined chute over which the conveyer operates, a screen between the conveyer and the bottom of the chute and a baffle-plate extended downward from the end of the chute 100 and forward of which drainage is directed by the closed bottom of the chute, substantially as specified.

2. In a clarifier, a tank divided into compartments, the separation between the compartments comprising a partition extending from the bottom of the tank and another partition extended from a point above the first-named partition to a point slightly above the bottom of the tank, and an endless conveyer 110 for removing scum from liquid passing through the tank, substantially as specified.

3. In a clarifier, a tank divided into compartments, an inclined partition in the inlet end of the first compartment, the bottom of 115 said partition being spaced above the bottom of the tank, a pipe for discharging liquid to be clarified into the tank at the upper side of said partition, an upwardly and outwardly inclined chute above the partition, a sieve 120 spaced above the bottom of the chute, an endless conveyer operating over said sieve, and means for operating the conveyer, substantially as specified.

4. In a clarifier, a tank comprising two compartments, the said compartments being formed by a partition extended upward from the bottom of the tank and having a valve-controlled opening in its lower portion, and a partition spaced from the first-named partition within the second compartment, the last-named partition being extended from a point above the first-named partition to a point 125 nearly to the bottom of the tank, steam-coils

arranged in the compartments, a conveyer operating in the first compartment for removing scum, an outlet-pipe, and a level-regulator connecting with said outlet-pipe, substantially as specified.

5. In a clarifier, a tank divided into compartments, a conveyer operating in one compartment for removing scum, steam heating-coils in the compartments, an outlet-pipe, a regulator comprising upwardly-extended telescopic sections connecting with the outlet-pipe, means for regulating the upper portion of the regulator relatively to the lower portion, and a valve arranged in the outlet-pipe, substantially as specified.

6. A clarifier, comprising compartments adapted to discharge one into the other, an endless conveyer for removing scum from the liquid passed into the first compartment,

coiled pipes arranged in the compartments and having connection with a steam-supply, and a propeller operating to force scum toward the conveyer, substantially as specified.

7. A clarifier, comprising a tank divided into compartments by two partitions so arranged that the liquid passing from one compartment will flow over one partition and underneath the other partition to the next compartment, means for conveying scum away from the liquid in the tank, and means for regulating the height of liquid in the tank, substantially as specified.

8. In testimony whereof I have signed my name to this specification in the presence of two subscribing witnesses.
